UNITED STATES PATENT OFFICE.

DELSON BREEDING, OF TULSA, OKLAHOMA.

CONTROL HEAD.

Application filed May 26, 1920, Serial No. 384,441. Renewed September 13, 1922. Serial No. 588,080.

To all whom it may concern:

Be it known that I, DELSON BREEDING, a citizen of the United States, and a resident of Tulsa, in the county of Tulsa and State 5 of Oklahoma, have invented certain new and useful Improvements in Control Heads, of which the following is a specification.

My invention relates generally to well drilling apparatus, and particularly to control heads of the type embodied in my co-pending application filed February 16, 1920, Serial No. 358,812, wherein valves are provided which prevent an escapement of oil from the control head while the usual oil 15 sealing device is being applied or removed when the drill cable is in the control head.

A purpose of my present invention is the provision of a control head in which the valves are supported for movement in arcs 20 of the same circle so that in closed position their confronting edges meet and thus provide a more efficient seal for preventing the passage of oil between the valves and drill cable.

It is also a purpose of my invention to provide a control head having valves which are so shaped as to utilize the pressure of the oil within the control head in securing the valves in closed position, one of the 30 valves being of greater dimensions than the other to permit a complete closing of one port independently of the other valve when the drill cable is withdrawn from the head.

I will describe one form of control head 35 embodying my invention, and will then point out the novel features thereof in claims.

In the drawings:

Figure 1 is a view showing in top plan, one form of control head embodying my invention.

Figure 2 is a vertical longitudinal sectional view of the control head shown in Figure 1.

Figure 3 is a transverse sectional view of 45 the control head shown in Figure 1, with the valves in closed position, and a conventional form of sealing device applied to the head.

Figure 4 is a detail perspective view of 50 one of the valves shown in Figures 2 and 3.

Similar reference characters refer to similar parts in each of the several views.

Referring specifically to the drawings C 55 designates generally a casing which is of substantially the same construction as the casing shown and described in my co-pending

application above referred to. The casing C in the present instance is formed with an upper aperture 15, a lower aperture 16, and at its ends with a pair of apertures 17 and 18. Communicating with the lower side of the casing C, through the aperture 16, is a pipe P which is adapted to extend into the well and receive the control cable K, as clearly shown in Figure 3. A pipe P' communicates with one end of the casing through the aperture 17, and this pipe is adapted to be connected to the pipe line for conveying the oil from the well which passes upwardly through the pipe P, and through the casing 70 C into the pipe P'. As shown in Figures 2 and 3, the walls of the aperture 15 are shaped to provide a shoulder 15^a upon which is supported an oil sealing device designated generally at O. As shown in Figure 3, the 75 sealing device O is of standard construction, and embraces the cable K in a manner to prevent the passage of oil through the aperture 15 while at the same time allowing of the free longitudinal movement of 80 the cable. The sealing device O is adapted to be secured within the aperture 15 by means of set screws 19, as shown in Figures 1 and 3.

As shown in Figures 2 and 3, V and V' 85 designate valves, each of which comprises a stem 20 or 20^a upon one end of which is formed a head 21 or 21^a. As illustrated to advantage in Figure 2, the heads 21 and 21^a are of arcuate formation and are formed 90 integrally with and extend laterally from discs 22 and 22^a formed on the inner ends of the stems 20 and 20^a, respectively. The confronting edges of the heads 21 and 21^a are formed at corresponding points with 95 semi-circular recesses 23 and 23^a, respectively, so that when the valves are in closed position as shown in Figure 3, the two recesses are in registry. As shown in Figure 3, the confronting edge of one head 21 or 21^a 100 is beveled or tapered transversely in a direction opposite to that of the confronting edge of the other head, so that with the edges contacting with each other, a diagonal joint is formed between the two valve heads 105 for a purpose which will be hereinafter described. As also shown in Figure 3, the inner surfaces of the heads 21 and 21^a are provided with flattened portions 24 and 24^a, respectively, at points adjacent their meeting edges, such flattened portions assuming 110 a substantially horizontal position when the

valves are in closed position so as to provide surfaces against which oil is adapted to impinge for maintaining the valves in closed position, as will be more clearly described 5 hereinafter. As shown in Figure 4, the head 21^a of the valve V' is provided at its free end with a ring 25 which is adapted to contact with the inner wall of the control head at a point adjacent the aperture 17, the 10 opening in the ring allowing of the free passage of oil through the aperture and into the pipe P' at all times, irrespective of the position of the valve.

The heads of the valves V and V' are 15 mounted for movement in the path of arcs of the same circle by means of the stems 20 and 20^a, the stem 20 being of tubular formation as shown in Figure 2, and rotatably receiving the stem 20^a. The stem 20 is rotatably supported in a plate L secured to the casing in the manner shown, such plate closing the aperture 18. With the stems 20 and 20^a mounted in the manner just described, it will be seen that the discs 22 and 25 22^a are arranged one in advance of the other, the disc 22 being disposed adjacent the inner wall of the plate L and contacting at its periphery with the inner wall of the casing C.

As shown in Figure 3, a pipe P² communicates with the control head casing at a 30 point between the sealing device O and the valves V and V'. This pipe P² serves as a drain for the small amount of oil and gas which leaks past the valves V and V'. The 35 passage of oil or gas through the pipe P² is controlled by a valve V² so that when such valve is opened, the oil and gas from above the valves V and V' are free to pass out of the casing through such pipe. It will be 40 understood that the valve V² is to be opened from time to time to effect a removal of the oil and gas, this preventing the latter from creating a pressure below the sealing device to cause it to be projected upwardly during 45 removal.

In the operation of the valves V and V', they are moved in opposite directions from 50 their closed positions as shown in Figure 3 to allow of the passage of the drilling tools and cables through the control head and downwardly within the pipe P. After the drilling tools have been properly positioned within the well so that the cable K is centered within the control head, the sealing device O is then applied to the aperture 15. The drilling operation may now proceed in 55 the usual manner, so that when oil rushes into the control head, the sealing device O prevents the escapement of oil through the aperture 15, thereby directing the same through the aperture 17 and into the pipe P'. After the drilling operation has been completed and it is desired to withdraw the tool 60 from the well, the valves V and V' are moved to closed position as shown in Figure 3,

wherein it will be seen that the recesses 23 and 23^a allow of the closing of the valves while the cable is centered within the control head so that the sealing device O can be removed from the head without allowing the oil to escape. After the sealing device O has been removed, the cable is elevated until the drilling tools are within the control head, whereupon, the valves V and V' are again moved to their open position to permit 70 the withdrawal of the tools from the control head. As soon as the tools have been removed, the valve V is moved to such a position that it completely closes the aperture 15. If it is desired at any time to again 80 insert the drilling tools and cable within the well, it is obvious that the sealing device O can be readily applied to the control head without permitting the escapement of an appreciable amount of oil, by proper manipulation of the valves V and V'.

It is to be particularly noted that when the valves V and V' are in closed position as shown in Figure 3, upward pressure of the oil and the gas within the control head acts on the surfaces 24 and 24^a to maintain the valves in closed position, thus preventing the accidental opening of the same during the application or removal of the sealing device to the control head. It is to be further noted that the diagonal joint between the confronting edges of the valve heads reduces the amount of oil that escapes through the recesses 23 and 23^a so that the frequent manipulation of the valve V² to 100 effect the drainage of this oil from the control head is rendered unnecessary.

Although I have herein shown and described one form of control head embodying my invention, it is to be understood that various changes and modifications may be made herein without departing from the spirit of the invention and the spirit and scope of the appended claims.

What I claim is:

1. A control head comprising a casing having apertures formed therein adapted to permit the passage of a drilling cable and tools therethrough, a valve within the casing movable to prevent the passage of fluid through one of said apertures, and a second valve movable within the casing and adapted to coact with the first valve to also prevent the passage of fluid through said aperture, said valves being movable in arcs of the same circle and having their confronting edges formed with recesses adapted to receive the drilling cable when the valves are moved to restrain the flow of fluid through said aperture.

2. A control head comprising a casing having apertures formed therein adapted to permit the passage of a drilling cable and tools therethrough, and a pair of valves within said casing movable in arcs of the

110

same circle, said valves having their confronting edges formed with recesses and their inner surfaces with flattened portions adapted to utilize the pressure of oil and gas within the casing in maintaining the valves in closed position.

3. A control head comprising a casing having apertures therein adapted to permit the passage of a drilling cable and tools therethrough, and a pair of valves within said casing and movable in arcs of the same circle, the confronting edges of said valves being beveled in opposite directions and formed with recesses, and the inner surfaces of said valves being formed with flattened portions adjacent their confronting edges for the purpose described.

4. A control head comprising, a casing having apertures formed therein adapted to permit the passage of a drilling cable and tools therethrough, a valve within the casing movable to prevent the passage of fluid through one of said apertures, said valve comprising, an arcuate head, a disc formed

on one end of the head, a stem secured to the disc, and a ring formed on the opposite end of the head, and a second valve movable within the casing and adapted to coact with the first valve to also prevent the passage of fluid through said aperture, the second valve comprising an arcuate head, a disc formed on one end of the head, and a tubular stem fixed to said disc and rotatably mounted in said casing, said tubular stem rotatably receiving the stem of the first valve.

5. A control head comprising, a casing having apertures formed therein adapted to permit the passage of a drilling cable and tools therethrough, a valve within the casing movable to prevent the passage of fluid through one of said apertures, a second valve movable within the casing and adapted to coact with the first valve to also prevent the passage of fluid through said aperture, and a ring formed on the first valve adapted to contact with one of the walls of said casing and to encircle one of the apertures.

DELSON BREEDING.
